Des. 187,464
Patented Mar. 22, 1960

187,464

FLEXIBLE FABRIC FOR USE AS A CEILING, WALL DRAPE, DIVIDER OR THE LIKE

Edward D. Stone, New York, N.Y.

Application February 20, 1958, Serial No. 49,728

Term of patent 14 years

(Cl. D13—1)

Fig. 1 is a front face view of a flexible fabric, showing my new design;

Fig. 2 is an enlarged fragmentary rear view of the top left corner thereof; and,

Fig. 3 is a section taken in the plane of the line 3—3 of Fig. 2.

I claim:

The ornamental design for a flexible fabric for use as ceiling, wall drape, divider or the like, substantially as shown.
